H. HEDRICH

PADLOCK

Filed April 9, 1927

INVENTOR-
H. Hedrich
BY
J. Ledermann
ATTORNEY

UNITED STATES PATENT OFFICE.

HERMAN HEDRICH, OF BROOKLYN, NEW YORK.

PADLOCK.

Application filed April 9, 1927. Serial No. 182,201.

The main object of this invention is to provide a novel type of padlock which is simple in construction, consisting of very few parts, inexpensive in cost of manufacture, and is positive in its locking functions.

Another object of this invention is to provide a padlock which has for its principal feature the characteristic that it is doubly locked upon withdrawal of a key, and remains locked even tho the key is inserted until such time as the hasp of the padlock is manipulated by sliding said hasp longitudinally along the body of the lock after which the hasp can be rotated to the open position.

The above and other objects will become apparent in the description below in which characters of reference refer to like-named parts in the drawing.

Referring briefly to the drawing, Figure 1 is an exterior side elevational view of the padlock, showing the same in closed position.

Figure 2 is a longitudinal sectional side elevational view of the same.

Figure 3 is a cross sectional view taken on line 2—2 of Figure 2.

Figure 4 is a longitudinal sectional elevational view taken on line 4—4 of Figure 2.

Figure 5 is a perspective view of the key used with the padlock for spreading the locking elements.

Figure 6 is a cross sectional view similar to Figure 3 showing the locking cage with its jaws spread apart to release the locking hasp of the padlock.

Referring in detail to the drawing the numeral 10 indicates the outer cylinder which constitutes the barrel of the padlock. This barrel has an inner shell 11 slipped into it, the latter shell receiving the entire mechanism which engages one end of a hasp 12. The opposite end of the hasp is rotatably mounted on a stud 13 whose ends are anchored in the wall of the inner shell 11. Both ends of the hasp pass into the chamber 16 of the inner shell 11 thru slots 15 and 17. The end 14 of the hasp which passes thru the slot 15 has a slot 18 at its lower end across which the stud spans.

Intermediate the length of the inner shell 11 a pin 19 extends diametrically across the inner shell and the ends thereof are anchored in the walls of the inner shell. The opposing ends of a coil spring 20 are connected to

the pin 19 and stud 13 by providing holes in the pin and stud and passing the ends of the spring thru these holes thereafter bending the protruding ends. Slots 21 are formed in the wall of the inner shell 11 and the ends of the stud 13 are inserted into the slot the stud being slideable longitudinally in said shell and barrel.

The other end of the hasp 12 has a downwardly extending tongue integral therewith which is indicated by the numeral 23, which tongue extends from the end 22 of the hasp 12. This tongue is provided with a notch 24 formed in its side. The tongue is square in cross section and its outer side is provided with the notch while two sides which are at right angles to the side having the notch is provided with locking grooves 25, one groove on each face of the tongue. The entering edge of the tongue is cammed at 26 for purposes which will be hereinafter fully described.

A ledge 27 extends horizontally in the chamber 16 from a plate 28 which latter is mounted adjacent the end wall 29 of the barrel, said plate and wall 29 having a slot 30 passing therethru thru which a key 30 is inserted.

A locking cage is mounted at the bottom of the inner shell 11. This cage consists of a U-shaped member 31 having upright resilient walls 32 from which lips 33 extend toward each other. These lips are separated by a channel 34 into which the tongue of the hasp inserts.

The key 30 comprises a flat plate which has a pair of prongs 35 and 36 extending therefrom in parallel relation. These prongs are separated by a channel 37 which is of sufficient width to receive the tongue 23 when the key is being introduced into the padlock. The external corners of the prongs are rounded as shown by the numeral 38 and these rounded portions of the prongs first engage the walls 32 of the locking cage and spread the latter apart.

The user of the padlock must be trained to use the same as the hasp is doubly locked in place in the barrel, once with the key and once with the spring 20. The spring being firmly anchored to the pin 19 at one end and at its opposite end secured to the stud 13 normally slides the latter toward the opposite end of the barrel, it being noted that

the stud 13 is slidably mounted in the slots 21 which are located in the inner shell 11 and are concealed from view by the barrel. The spring 20 urges the end 22 of the hasp 12 toward the ledge and the notch 24 in the tongue 23 receives the edge of the ledge 27 and thereby latches the hasp in closed position. When the hasp is in open position and it is desired to lock the same, the tongue 23 is depressed into the slot 17. The rounded end 39 of the tongue passes into the channel 34 and spreads the lips 33 apart until the grooves are aligned with the lips when the resiliency of the walls 32 of the cage extend 15 the edges of the lips 33 into the grooves 25. As this movement occurs the cammed nose 26 of the tongue rides on the edge of the ledge 27 and the entire hasp by this engagement is moved rearwardly against the tension of 20 the coil spring 20 until the instant that the notch 29 opposes the ledge 27, after which the entire hasp moves forwardly toward the ledge, the padlock being then both locked against opening without a key and securely 25 latched. To open the padlock the prongs 35 and 36 are inserted into the barrel thru the wall 29. The rounded ends of these prongs are the first portions of the prongs to engage the surfaces of the walls 32 of 30 the locking cage and spread these walls apart thereby removing the lips from the grooves which disengages the locking means from the hasp but does not disengage the locking means. By sliding the hasp 12 against the tension of the spring in the inner shell until the ledge 27 is removed out of the notch 24, the latching means is thereafter released and the hasp may be freely 35 rotated to open position.

40 It is to be noted that certain changes in form and construction may be made without departing from the spirit and scope of the invention.

I claim:

45 1. In a padlock, a barrel having slots therein, a curved hasp slidably and pivotally mounted in said barrel, a slidable stud pivoting one end of said hasp in said barrel, said stud being slidable in said barrel, and 50 means in said barrel for simultaneously

latching and locking said hasp in closed position.

2. In a padlock, a barrel having longitudinal slots therein, a stud slidably mounted in said barrel, said ball comprising an outer circular and an inner shell a pin rigidly mounted in said barrel, a coil spring connected to said pin and stud, a curved hasp, one end of said curved hasp swinging on said stud, a tongue on the opposite end of said hasp, said tongue having a notch on one slide and a groove on each of the intersecting sides, a flexible cage engaging said grooves, and a ledge in said barrel engaged normally in said notch for latching said hasp in locked 65 position.

3. In a padlock, a barrel, a ledge rigid in said barrel, a unitary resilient cage in said barrel normally in locking position, a hasp pivotally mounted in said barrel, a stud pivoting said hasp, said stud being slidable in said barrel, said hasp having a notch thereon, a spring in said barrel normally urging the hasp forwardly to cause the ledge to register in said notch for latching said hasp, 70 grooves in said hasp, and lips on the cage engaged normally in the grooves of the hasp when the latter is in locked position.

4. In a padlock, a barrel, a horizontal ledge mounted rigidly in said barrel, a cage adjacent said ledge, said cage having resilient upright walls thereon, lips projecting from said walls toward each other, said lips being separated by a channel, a hasp having one end rotatably and slidably mounted in said barrel, a tongue on the free end of said hasp, said tongue being square in cross section and having a notch on one side and grooves on opposing sides, said tongue inserting in the channel to spread the lips apart when being inserted into the barrel, the lips resting the grooves when said hasp is locked in place, and a key having prongs thereon, the prongs being inserted into the barrel to spread the walls of the cage to widen the channel and spread the lip out of 85 said grooves.

In testimony whereof I affix my signature.

HERMAN HEDRICH,
